UNITED STATES PATENT OFFICE.

DOMENICO TUSO, OF BURBANK, CALIFORNIA.

AMUSEMENT DEVICE.

Application filed November 11, 1920. Serial No. 423,334.

To all whom it may concern:

Be it known that I, DOMENICO TUSO, a citizen of the United States, residing at Burbank, in the county of Los Angeles and State of California, have invented new and useful Improvements in Amusement Devices, of which the following is a specification.

It is the object of this invention to provide an amusement device in the nature of 10 an aerial swing.

More particularly, it is the object of the invention to provide a plurality of suspended carriages adapted to carry passengers and arranged to be swung in a circle and at the 15 same time elevated and lowered, the carriages swinging freely radially of the rotatable support during the operation of the device.

The invention will be readily understood 20 from the following description of the accompanying drawing showing a side elevation, partly in vertical section, of the device constructed in accordance with the invention.

25 The device comprises a support 1 which may be of any preferred construction. At the upper end of this support is arranged a bearing 2 having its axis inclined with relation to both the vertical and the horizontal 30 and, preferably, disposed at an angle of 45°. A shaft 3 is journaled in this bearing and projects beyond the same with the hub 3a of a wheel 4 fixed upon said projection. The wheel is thus disposed at an angle of 45°.

35 The wheel is provided with spokes 5 which include turnbuckle 6 for tightening the same, and braces 7 are, preferably, also extended from the rim 8 of the wheel to a brace rod 9 projecting axially beyond the wheel.

40 The shaft 3 is provided with an operating connection for rotating the same, said operating connection including a gear 10 fixed upon shaft 3 and meshing with a bevel pinion 11 carried by a drive shaft 12 journaled in the frame 1. The end of shaft 12 opposite pinion 11, preferably, extends to the base of frame 1 and is provided with a bevel gear 13 meshing with a bevel pinion 14 carried by the shaft of a suitable operating 45 means shown as an electric motor 15. By

this arrangement the motor is adapted to rotate the wheel 4.

The rotatable wheel is of such diameter that its rim 8 is positioned outwardly beyond support 1, and a plurality of carriages 55 16 are swingably suspended from the rim 8. These carriages are adapted to carry passengers and are suspended at their respective ends by looped supports 17 from eyes 18 which are pivoted to eyes 19 projecting 60 radially beyond the rim 8.

The suspension of the carriages by supports at their respective ends and the angular disposition of the wheel 4, will cause the carriages to be tilted as they are swung 65 around with the wheel 4, and at the same time the carriages will be raised and lowered through the angular disposition of the wheel. It will also be noted that the pivotal mountings provided by co-operating eyes 18 70 and 19 will permit radial swinging movement of the suspended carriages as shown in dotted lines in the drawing.

An aerial swing is thus provided in which the carriages carrying the passengers are 75 swung back and forth and at the same time are tilted longitudinally and raised and lowered.

Various changes may be made without departing from the spirit of the invention as 80 claimed.

What is claimed is:

1. An amusement device comprising a support, an inclined bearing sustained on the support, a shaft journaled in the bearing, a wheel fixed to the shaft, a gear fixed to the shaft between the wheel and bearing, a second shaft disposed vertically within the support, driving means operatively connected to the second shaft, a gear fixed to the 85 second shaft and meshing with the first gear whereby rotation of the wheel is effected, eyes projecting radially from the periphery of the wheel, and hooks engaging the eyes, and passenger carrying members sustained 90 from the hooks so as to be normally disposed in a vertical plane.

2. An amusement device comprising a support, an inclined bearing sustained on the support, a shaft journaled in the bear- 100

ing, a wheel fixed to the shaft, a gear fixed to the shaft between the wheel and bearing, a second shaft disposed vertically within the support, driving means operatively connected to the second shaft, a gear fixed to the second shaft and meshing with the first gear whereby rotation of the wheel is effected, extensions projecting radially from the periph-

ery of the wheel, elements engaging the extensions, and passenger carrying members sustained from the elements so as to be normally disposed in a vertical plane.

In testimony whereof I have signed my name to this specification.

D. TUSO.
